(57) **CLAIM**

The ornamental design for a temporary safety rail support bracket, as shown and described.

DESCRIPTION

FIG. 1 is a rear view of a temporary safety rail support bracket showing my new design.

FIG. 2 is a front view of the temporary safety rail support bracket.

FIG. 3 is a side view of the temporary safety rail support bracket.

FIG. 4 is a top view of the temporary safety rail support bracket.

FIG. 5 is a bottom view of the temporary safety rail support bracket; and,

FIG. 6 is a perspective view of a temporary safety rail support bracket.

The broken line showing of a partial housing structure and rails is for illustrative purposes only and forms no part of the claimed design.
